[57] CLAIM

The ornamental design for a parking space reserver, as shown and described.

DESCRIPTION

FIG. 1 is a top perspective view of a parking space reserver showing my new design, the broken lines showing a padlock for illustrative purposes only; FIG. 2 is a rear perspective view thereof; FIG. 3 is a top plan view thereof in the swung down position; FIG. 4 is an end elevational view of FIG. 3; and FIG. 5 is a side elevational view of FIG. 3, the opposite side being a mirror image of the side shown.
